UNITED STATES PATENT OFFICE.

GEORGE P. RASCK, OF DES MOINES, IOWA, ASSIGNOR OF ONE-THIRD TO
MONRAD JOHN OLSEN, OF DES MOINES, IOWA.

WINDMILL.

SPECIFICATION forming part of Letters Patent No. 749,095, dated January 5, 1904.

Application filed April 11, 1903. Serial No. 152 243. (No model.)

To all whom it may concern:

Be it known that I, GEORGE P. RASCK, a citizen of the United States, residing at Des Moines, in the county of Polk and State of Iowa, have invented certain new and useful Improvements in Windmills, of which the following is a specification.

This invention relates to windmills; and its objects are to provide an improved gearing for transmitting movement from the wind-wheel to the pump-rod, to provide an improved mechanism for operating the vane and a wind-wheel brake, and generally to improve and simplify the construction of the wind-mill-head and many of the parts supported thereby.

The invention will be fully described hereinafter, reference being had to the accompanying drawings, in which—

20 Figure 1 is a plan view of the head and the operating mechanism supported thereby, the vane being at a right angle to the face of the wheel. Fig. 2 is a side elevation showing the vane-socket parallel to the face of the wheel. 25 Fig. 3 is an end view partly broken away. Fig. 4 is a face view of the gearing to operate the pump-rod. Fig. 5 is a sectional view on the line 5 5 of Fig. 4.

The numeral 10 indicates the upper end 30 portion or cap-piece of a tower, and 11 a head-casting mounted on and extending upwardly from the cap-piece and stepped for rotation therein on a vertical axis. The casting is provided with bearings 12 for the wind-wheel shaft 13, which, as shown, projects beyond the bearings at both ends. Near one end the shaft is provided with a hub 14, rigidly connected thereto, whereby a wind-wheel (not shown) may be attached to said shaft, 40 and a driving-pinion 15 is rigidly connected to the shaft near its other end. Suitable oil-cups 16 may be provided on the bearings for the purpose of lubricating the shaft.

A frame 17 is rigidly connected to the upper part of the head 11, and this frame is 45 open in its middle portion, such opening being of sufficient size to permit the vertical and lateral movement of an internal gear 18, with which the pinion 15 meshes. The internal gear 18 is of oblate form, preferably

with long parallel sides and rounded ends, the rounded ends being eccentric to and on an arc greater than the pinion 15. A pitman 19 is fixed to or formed integrally with one end of the internal gear. The pitman 19 extends from the internal gear at one side of its vertical median line, and the parts are so arranged that when the pinion 15 is lifting the internal gear the pitman and the pump-rod 20, connected to it, will be truly vertical, thus insuring a direct lift of the pump-rod. 55

A back plate 21 of annular and oblate form is formed on the rear edge of the gear 15, and a flange 22 of annular and oblate form is formed on the back plate 21 concentric or incident with the inner margin of said back plate, and to the edge of this flange a base-plate 24 is secured, said base-plate being parallel with the back plate 21. A rib or partition 25 is formed on the inner face of the base-plate 24 midway of the oblate space inclosed by the flange 22, or, in other words, in the median line of the internal gear, and the side and end surfaces of the rib 25 are spaced from the inner surface of the flange 22 a distance 60 slightly greater than the diameter of the shaft 13, thus forming a groove or guideway, (indicated by 26.) The shaft 13 extends beyond the pinion 15 and is reduced in diameter to form a spindle 27, upon which a roller 28 is 65 mounted to turn. The diameter of the roller is slightly less than the width of the guideway 26, and its length is substantially equal to the depth of the guideway. The function of the roller 28 is to engage lightly with rolling contact one or the other of the walls of the groove 26, and thus hold the internal gear in mesh with the pinion when the latter is being rotated by the wind-wheel. 70

It is necessary to provide some means for 75 preventing the gear and pinion from becoming disengaged and also to guide the gear in its vertical movement, and while this may be accomplished in various ways I prefer to provide a roller 29, journaled in bearings 30, connected to the frame 17, said roller engaging the outer face of the base-plate 24. The shaft 13 will of course be prevented from moving endwise in its bearings, and the end of the spindle 29 by its engagement with the bottom 80 85 90 95 100

of the groove 26 will prevent the gear from moving away from the pinion in one direction, and the roller 29 will prevent such movement in the other direction.

5 31 indicates a vertically-extending rod which projects at its upper end through an opening in the frame 17, and a collar 32 fits loosely over said rod and is supported by the frame 17, a washer 32^a being interposed between them. A cotter-pin 33 extends through the rod 31 and rests upon the collar to limit the downward movement of the rod. The collar 32 constitutes an eye, to which the upper end of the vane-brace (not shown) may 15 be attached in any suitable manner.

A tube 34 fits loosely on the lower portion of the rod 31, said tube being formed with a vane-socket 35, adapted to receive and support the vane-arm 35^a. One end of the tube, 20 in the present case the lower end, is provided with ratchet-teeth 36, and a collar 37, loose on the rod 31, is provided with a ratchet 38, adapted to coöperate with the teeth 36. The lower end of the rod 31 extends loosely through 25 an ear 39, projecting from the head-casting 11. A spiral spring 40 surrounds the rod 31 and in the present case is located between the collar 37 and ear 39. One end of the spring engages a projection 41 on the collar 37, and 30 the other end of the spring engages a fixed part of the head-casting, shown in the present case as a projection 42 on the ear 39. The ends of the spring may be loosely engaged with the projections, or they may be rigidly 35 secured to the collar and head-casting, if preferred. A cotter-pin 43 in the rod 31 engages the upper end of the tube 34 and prevents upward movement of the tube on the rod, and preferably a washer 43^a is interposed between 40 the tube and pin. A pin 44 is removably secured in the rod 31 to engage the under face of the ear 39, and thereby prevents upward movement of the rod.

A chain 45 is connected at one end to the 45 vane-arm 35^a and passes around a pulley 46, journaled in a support 47, projecting from the head-casting 11, thence over a pulley 48 and into the tubular lower end of the head-casting 11, which is supported to turn in the tubular cap-piece 10. The chain extends through the cap-piece 10 nearly down to the turn-swivel 49^a, which connects the lower end of the pitman 19 to a piece of tubing 20^a, which is connected at its lower end to the pump-rod 50 55 20. To the end of the chain 45 a wire 49 is connected, and said wire extends down through the swivel 49^a and tube 20^a to near the ground to be in position to be grasped. The wire 49 is in two sections, connected by 60 a swivel 60. By pulling on the wire the vane-socket will be moved from the position shown in Fig. 1 to that shown in Fig. 2, and during such movement the tube 34 and collar 37 will turn on the rod 31 and put tension on the 65 spring 40, and as soon as the wire is released the said spring will operate to turn the vane-socket to the position indicated in Fig. 1.

Any desired tension can be put on the spring 40 by removing the pin 44 and then turning the collar, the latter preferably having flat 70 faces on its periphery, to which a wrench may be applied. In turning the collar the tube 34 and rod 31 will be lifted as the ratchet 38 moves from one tooth to the next. It is desirable when the vane is turned to be parallel 75 to the face of the wheel that the wheel be positively prevented from turning, and in order to do this the socket is provided with a plain annular flange 50, with which a brake-shoe 51 is adapted to engage. This shoe is 80 supported by a pair of arms 52, pivoted to the upper portion of the head-casting 11. A lever 53 is pivoted between its ends to the lower portion of the head-casting 11, and one of its arms extends into the path of movement of a 85 projection 54, extending down from the socket 35, to engage the curved end 55 of said arm and depress it. The outer end of the other arm is connected by a link 56 to the brake-shoe. Preferably the connection between 90 the lever 53 and the link 56 is adjustable in order that wear may be taken up and the degree of pressure of the brake on the flange 50 be varied. A very simple device for effecting this adjustment is shown in the drawings, 95 where it will be seen that the lever is provided with an opening through which the end 56^a of the link extends loosely. This end is threaded, and a nut 58 is fitted on it and engages the upper surface of the lever 53. 100

The operation of the several parts will be readily understood from the foregoing description.

One of the principal advantages of my invention is that by the use of the elongated 105 internal gear with its pitman to one side of its median line I am enabled to get a long stroke and a direct pull on the pump-rod when it is being lifted. Further, by the means employed to guide the internal gear it will be 110 impossible for it to become disengaged from the pinion. The internal gear arranged as in my invention will produce the long stroke with a light as well as with a strong wind, although, of course, it will be slower. Here- 115 tofore when a crank-wheel has been employed for the purpose of effecting a long stroke the upward pull on the pump-rod is nearly all indirect, and consequently with a light wind there is frequently not sufficient power to lift 120 the pump-rod.

Without limiting myself to the precise details of construction illustrated and described, I claim—

1. The combination with the head-casting 125 of a windmill, of a wind-wheel shaft journaled in the casting, a pinion on the shaft, a vertically-elongated internal gear meshing with the pinion, a pitman extending downwardly from the gear at one side of its median line, 130 and a pump-rod connected directly to the pitman, whereby when the gear is operating to lift the pump-rod both will be in a vertical position, substantially as set forth.

2. The combination with the head-casting of a windmill, of a wind-wheel shaft journaled in the casting, a pinion on the shaft, a vertically-elongated internal gear meshing with the pinion, means on the head-casting for holding the gear and pinion in engagement, a pitman extending downwardly from the gear at its lifting side, and a pump-rod connected directly to the pitman, whereby when the gear is lifting the pump-rod the latter will be in vertical alinement with the wind-wheel shaft, substantially as set forth. 5
3. The combination with the head-casting of a windmill, of a wind-wheel shaft journaled in the casting, a pinion on the shaft, a vertically-elongated internal gear meshing with the pinion, a roller supported in bearings on the head-casting and engaging the back face of the internal gear for holding the latter in engagement with the pinion, a pitman extending downwardly from the gear at one side of its median line, and a pump-rod connected to the pitman, substantially as set forth. 10
4. The combination with the head-casting of a windmill, of a wind-wheel shaft journaled in the casting, a pinion on the shaft, a vertically-elongated internal gear meshing with the pinion, a guiding-groove 26 in said gear in parallel relation to the teeth thereof, a roller 20 on the shaft entering said groove, a pitman extending from the gear in line with the groove on the lifting side of the gear, and a pump-rod connected directly to said pitman, substantially as set forth. 25
5. In a windmill, the combination with the head-casting, of a vertically-extending rod supported by said casting, a sleeve fitting over said rod and having a vane-socket, one end of the sleeve having ratchet-teeth thereon, a collar on the rod adjacent to the sleeve 40 and having a ratchet to engage the teeth, a spiral spring on the rod having one end engaged with a fixed part of the head-casting and the other with said collar, and means for turning said sleeve against the tension of the 45 spring, substantially as set forth.
6. In a windmill, the combination of a head-casting, a wind-wheel hub supported by the casting and having a braking-surface, a vane-socket pivotally supported on said casting, a 50 brake-shoe movably supported by said casting in position to engage the said braking-surface on the hub, a lever pivoted between its ends to the casting and one arm extending in the path of movement of the vane-socket to be operated thereby, a link connecting the outer end of the other arm of the lever to the brake-shoe, and means for adjusting the length of the link between the opposing faces of the lever and brake-shoe, substantially as set forth. 55

In testimony whereof I have signed my name to this specification in the presence of two subscribing witnesses.

GEORGE P. RASCK.
